(57) **CLAIM**

The ornamental design for an absorbent article substrate with a pattern, as shown and described.

DESCRIPTION

FIG. 1 is a front view of an absorbent article substrate with a pattern showing a first embodiment;

FIG. 2 is a front view of an absorbent article substrate with a pattern showing a second embodiment;

FIG. 3 is a rear view of an absorbent article substrate with a pattern shown in each of FIGS. 1 and 2;

FIG. 4 is a left side view of an absorbent article substrate with a pattern shown in each of FIGS. 1 and 2;

FIG. 5 is a right side view of an absorbent article substrate with a pattern shown in each of FIGS. 1 and 2;

FIG. 6 is a top plan view of an absorbent article substrate with a pattern shown in each of FIGS. 1 and 2;

FIG. 7 is a bottom plan view of an absorbent article substrate with a pattern shown in each of FIGS. 1 and 2;

FIG. 8 is a rear view of an absorbent article substrate with a pattern showing a third embodiment;

FIG. 9 is a rear view of an absorbent article substrate with a pattern showing the second embodiment applied to a different portion of the article

FIG. 10 is a rear view of an absorbent article substrate with a pattern showing a fourth embodiment;

FIG. 11 is a rear view of an absorbent article substrate with a pattern showing a fifth embodiment;

FIG. 12 is a front view of an absorbent article substrate with a pattern shown in each of FIGS. 8, 9, 10, and 11;

FIG. 13 is a left side view of an absorbent article substrate with a pattern shown in each of FIGS. 8, 9, 10, and 11;

FIG. 14 is a right side view of an absorbent article substrate with a pattern shown in each of FIGS. 8, 9, 10, and 11;

FIG. 15 is a top plan view of an absorbent article substrate with a pattern shown in each of FIGS. 8, 9, 10, and 11; and,

FIG. 16 is a bottom plan view of an absorbent article substrate with a pattern shown in each of FIGS. 8, 9, 10, and 11.
